CLAIM

The ornamental design for a T-nut workholder clamp, as shown and described.

DESCRIPTION

FIG. 1 is a perspective view of a T-Nut workholder clamp showing my new design, the broken lines representing a machine tool table and workpiece is shown for illustrative purposes only and forms no part of the claimed design;

FIG. 2 is a top plan view thereof;

FIG. 3 is a bottom plan view thereof;

FIG. 4 is a left side elevational view thereof, the right side being a mirror image;

FIG. 5 is a top plan view of a second embodiment thereof;

FIG. 6 is a bottom plan view thereof;

FIG. 7 is a left side elevational view thereof, the right side being a mirror image; and

FIG. 8 is a front elevational view of both embodiments, the rear being identical.
